UNITED STATES PATENT OFFICE.

ANDREW ONUFRYK, OF ROCHESTER, NEW YORK.

DESIGN FOR A DINING-CUTLERY HOLDER.

55,639.

Specification for Design.

Patented July 6, 1920.

Application filed March 12, 1920. Serial No. 365,323. Term of patent 7 years.

To all whom it may concern:

Be it known that I, ANDREW ONUFRYK, a citizen of Ukraine, residing at Rochester, in the county of Monroe and State of New York, have invented a new, original, and ornamental Design for a Dining-Cutlery Holder, of which the following is a specification, reference being had to the accompany drawing, forming part thereof.

The figure is a view in perspective of a dining cutlery holder, showing my new design.

I claim:

The ornamental design for a dining cutlery holder as shown.

ANDREW ONUFRYK.
